UNITED STATES PATENT OFFICE.

CHARLES HUNT, OF NEW YORK, N. Y.

DETACHING-GEAR.

1,252,116.

Specification of Letters Patent.

Patented Jan. 1, 1918.

Application filed May 17, 1916. Serial No. 98,007.

To all whom it may concern:

Be it known that I, CHARLES HUNT, a citizen of the United States, residing in the borough of Manhattan, city, county, and State of New York, have invented a new and useful Improvement in Detaching-Gears, of which the following is a description.

This invention has reference to detaching gear or releasing devices for lifeboats and other similar small boats, and particularly to improvements upon the structure disclosed and claimed in my application Serial No. 725,126, filed October 11, 1912.

Among the objects of my invention may be noted the following: to provide improved means by which the lifeboat may be quickly and simultaneously released or detached at both ends from the supporting tackle; to provide means by which the draft of the cable upon the releasing or detaching gear may be substantially direct and positive; to provide means by which the detaching gear is positively locked against release until the locking means have been manually removed; to provide means by which the holding mechanism of the detaching gear is prevented from being accidentally jarred loose or rendered capable of accidentally moving to release the supporting tackle; and to provide simple, compact and inexpensive means for carrying out the foregoing objects.

With the above objects in view, and others which will be detailed during the course of this description, my invention consists in the parts, features, elements and combinations thereof hereinafter described and claimed.

In order that my invention may be clearly understood, I have provided drawings wherein:

Figure 1 is a side elevation of a detaching gear, parts being broken away to curtail the figure, showing the same in locked, operative or supporting condition;

Fig. 2 is a central vertical section showing the detaching gear open or in released condition, parts being broken away to curtail the figure;

Fig. 3 is a top-plan view of the device shown in Fig. 1;

Fig. 4 is a front elevation of the device shown in Fig. 1, but showing a different form of releasing arm;

Fig. 5 is a side elevation of the pulley mechanism by means of which the cables are

manipulated to simultaneously release the detaching gear;

Fig. 6 is a view substantially on the line 6—6 of Fig. 5;

Fig. 7 is an inside view of a conventional form of lifeboat, the figure being broken in the middle to curtail the view, showing the manner of manipulating and releasing the detaching gear; and

Fig. 8 is a top-plan view of such boat, the figure being broken in two and the parts being slightly enlarged.

Referring to the drawings, and particularly to Figs. 1 to 4, inclusive, the frame of the device will be seen to consist of two side-members 1 and 2, joined by the back-member 3, and having the connecting web 4 above which the members 1 and 2 are formed with recesses forming a notch 5, in which the hook or other device 5^a of the supporting tackle is entered, said notch being formed between the two pairs of upright members 6 and 7, provided on the side-members 1 and 2, which afford, at their upper ends, journal-bearings for the pins 8 and 9, respectively. The pin 8 has the locking-lever 10, journaled thereon between the upright members 6, said locking lever cooperating with the notched end 11, of the holding-bar 12, journaled upon the pin 9, between the upright members 7. The said pin 9 may also be provided at its outer ends with a loop, hook, ring or other suitable means 13, capable of swinging over the holding-bar to support the detaching-gear, or boat to which the latter is secured, or which may be utilized to tie or anchor the boat when desired. The holding-bar is provided with a radial lug 14, one side of which is flat and which projects from the hub of the said holding-bar so that, when the latter is in holding position, as shown in Fig. 1, said lug 14 will engage the portion 15 of the back-member 3, thus enabling said holding-bar to drop into operative position and to be sustained in a substantially horizontal position, and be prevented from dropping between the members 6 and 7 of the hook. The locking-lever, at its opposite end, is pro-

vided with the extension 16, formed in continuity with the member 10, which cooperates with the holding-bar, the same being sufficiently extensive to rest, when in the position shown in Fig. 1, upon the lug 17 of

a latch, the upper end of which is weighted, as at 18, and the lower end of which is journaled upon a pin 19, supported by lugs 20, formed on the side-members 1 and 2, above 5 the web 4, and at one side of the uprights 6. The latch is also provided with a pin 21, extending at a right angle to the length thereof, and with which cooperates the cam-surface 22, and hook 23, of a tripping-dog, 10 journaled, as by the pin 24, upon the frame-extension 25, formed integral with one of the uprights 6. This extension 25 may be formed on either of the members 6 and extended at a right angle thereto from the top 15 thereof, according to whether a right or left hand detaching-gear is made. The pin 24 is squared at its outer end, as at 26, and supports thereon an operating arm or handle 27, the same being thereby prevented from 20 turning without also turning the tripping-dog. The arm 27 may be either straight, as shown in Fig. 1 and at the left end of Fig. 8, or it may be provided with offset portions, as shown in Fig. 4, and the right end of Fig. 25 8, the offset portions being indicated by 28 and 29. The extension 16 of the locking-lever, when in the position shown in Fig. 2, engages a lug 30, provided on one of the members 6, and by means of which the said 30 locking-lever is prevented from swinging too far upwardly when released from co-operation with the holding-bar. This prevents the locking-lever from turning over and dropping to the left, and thus becoming 35 objectionably engaged with the latch or other parts of the device.

At the extreme forward end of the side-members 1 and 2, the same are formed into bearings 31, for the support of a pin 32, 40 upon which is journaled a supporting-lever 33, having an arm 34, extending rearwardly into position slightly above the hub of the latch and into position to coöperate at its forward end with the hook 23 of the tripping-dog. At its upper end the supporting-lever is provided with a head 35, adapted to coöperate with the base of the weighted portion 18 of the latch, so as to support the latter in the position of Fig. 1 and slide 45 from under said weighted portion, as shown in Fig. 2, when operated upon by the tripping-dog. The base of the supporting-lever is provided with the limiting-member 36, in the form of a flat bar, the ends of which extend sufficiently beyond the base of the supporting-lever to engage the under surface of the bearings 31, whereby the supporting-lever, as shown in Fig. 2, is limited in its 50 outward movement and prevented from falling down beyond the position shown in said figure. The supporting-lever is also provided with a transverse groove or notch 37, for the reception of a locking-pin 38, adapted to be passed through the apertures 39, in 55 the upper portions of the bearings 31.

When the parts are in the position of Fig. 1, the locking-pin rests within the groove or notch 37 and holds the supporting-lever, so that its head or upper end 35 cannot be forced from under the weighted portion 18 70 of the latch. Hence, the parts will all be held rigidly in operative position, without possibility of release, regardless of the manipulation of the arm 27, until the locking-pin has been manually removed. In order 75 that the locking-pin may not be lost, it is attached through its eye 40 and chain 41 to one of the side-members 1 and 2. The shoulder 42, on the pin, prevents the same from sliding through the apertures into position such that, by possibility, the supporting-lever may be released partially or otherwise. 80

One of the detaching or releasing gears is secured at each end of the boat, Fig. 7, by 85 means of several bolts passing through apertures 43, in the back-member 3, the attachment generally being made through the medium of a block 44, firmly secured to the keel of the boat. At a convenient point on 90 the inside of one side of the boat, near the top thereof and under the rail, bracket-members are securely bolted, one of said members being provided with the base 45, and the offset arm 46, and the other member 47 95 being flat and the two being provided at their outer ends with bearings for the pin 48, one end 49 of which is squared for the reception of the manipulating - handle 50. The offset of the member 46, from the base 45, 100 enables the cable-drum to run freely between the two parts of the bracket, as will be readily understood upon reference to Figs. 5 and 6. The cable-drum consists of the pulley 51, the periphery of which is grooved to receive a cable, and the journal 52 of which is extended at one side and turns upon the pin 48, which is integral with the hub of the pulley 53, which latter is also circumferentially grooved to receive an operating cable. 105 Each of the pulleys is provided in its body with a plurality of circularly arranged apertures 54, through which a headed bolt 55 may be passed, one end of which has the removable nut 56 screwed thereon. By this means, the two pulleys are held together adjustably and operate as one, and slack in the cables can be taken up by relative adjustment. Each of the pulleys is also provided with an aperture 57, extending from the 110 base of the groove therein, to the web of the pulley, at which point the groove is extended by a rounded depression 58. The aperture is for the reception of the cable which works in the groove of the pulley and the recess 115 58 is for the reception of the knot or enlargement which holds the cable within the said aperture 57. As shown in Fig. 7, the cables are wrapped in opposite directions around the respective pulleys, and are held to the 120 125 130

peripheries thereof by being passed through the aperture and knotted as just stated. The crank 50 is held in inoperative position in any suitable manner, as by a loop 59, secured to the side of the boat within the operative range of the handle. This prevents accidental movement. Viewing Fig. 7, it will be seen that the cable 60 is secured to the pulley 51, while the cable 61 is secured to the pulley 53, one at the top and the other at the bottom of the respective pulleys when set and held in normal position, such as shown in Figs. 5 and 7. The cable 60 is led through a series of loops 62 under the rail of the boat to a pulley 63, and from thence to a pulley 64, held by bracket 65, at an angle to the pulley 63, and thence is connected to the operating-handle of the detaching-gear, in this instance an offset handle such as 29, Fig. 4. The cable 61 is passed through several guide-eyes 66, to the pulley 67, and thence to a pulley 68, both carried by a brace 69, or transverse bar of the boat specially provided therefor, and thence to the operating-handle of the stern-detaching gear, in this instance a straight handle 27, such as shown in Fig. 1.

It will now be understood that the boat to be launched will be suspended from the block-and-fall or supporting-tackle by means of the hook, ring or other device 5^a, Fig. 1, and that the strain upon the boat is equalized throughout its length by reason of such support at the opposite ends thereof. The said supporting means 5^a is first inserted within the recess 5, then the holding-bar 12 is turned down to horizontal position, the locking-lever is then turned into the position of Fig. 1, the latch is then pushed into the position of Fig. 1 under the extension 16 of the locking-lever, the supporting-lever 33 is then pushed under the head of the weighted latch, and the locking-pin 38 is then inserted through the apertures 39, thus seating it in the groove 37 of the supporting-lever. The operating-handle 27 will naturally assume the position of Fig. 1, owing to its weight, and, if not, the movement of the supporting-lever 33, operating through the medium of its arm 34, upon the hook 23 of the tripping-dog, will force the latter downwardly and consequently the operating-handle 27, the two devices assuming the position of Fig. 1. When the boat is lowered into the water, or at any time during its descent toward the water, it can be released from the supporting-tackle simultaneously at both ends by manipulating the lever 50. Ordinarily, however, the boat will be loaded on shipboard and connected to the supporting-tackle of the davits as just described, whereupon the launching mechanism will swing the boat outboard to clear the ship and will then lower the boat into the water. The locking-pins may be removed just before the boat is moved outboard, or said locking-pins may not be released until the boat is about to reach the water. The sailor sitting near one end of the boat, or on the seat adjacent to the operating-arm 50, will be in charge of the boat and will be on the watch to release the boat at the proper time. At the proper time, he will give the word to the men in the opposite ends of the boat to draw out the pins 38, thus enabling him by an upward movement of the lever 50 to exert a direct pull upon the operating-handles 27, 29, thus causing the tripping-dog, through its cam-surface 22, operating upon the pin 21 of the latch, to throw the latter outwardly, thus releasing the locking-lever and enabling the strain upon the supporting-tackle to immediately throw the holding-bar 12 into the position shown in Fig. 2. The boat is thus released and the sailors can at once dip their oars and row away.

From the foregoing it will be seen that it is impossible to release the boat from the launching apparatus until the pins 38 have been removed and that the strain of the boat upon the launching-tackle will prevent release of the boat until a positive pull is made upon the operating-handles 27, 29. This positive pull is produced by operation of the lever 50, which turns the pulleys 51, 53, simultaneously in the same direction and draws the cables 60, 61, in opposite directions, thus tripping the handles 27, 29, in opposite directions. It will also be seen that the pull is direct upon the handles 27, 29, that the slack in the cables 60, 61, can be taken up, so that the movement thereof will be simultaneous and equal instantly upon manipulation of the lever 50, and that the boat thereby can be evenly and instantly released at both ends from the supporting-tackle of the launching mechanism.

My detaching or releasing gear can be tripped automatically, if desired, this being accomplished by removing or leaving out the pins 38. The strain of the launching-tackle upon the holding-bar 12 will cause the extension 16 of the locking-lever 10 to tightly grip the latch with immense pressure, the latch being held in the upright position of Fig. 1 against ordinary shocks or attempts to move the same. When, however, the boat reaches the water and the launching-tackle, through its hook or loop 5^a, releases pressure upon the holding-bar 12, the tendency of the weighted head 18 of the latch will be to release the latter from the extension 16 of the locking-lever. Hence, lack of pressure on the locking-lever or a slight shock or jar of the boat, or of the releasing-gear, will cause the latch to shift from under the extension 16 of the locking-lever and thereby automatically release the

boat. 110

115

120

125

130

boat or the gear from the launching-tackle. It will be understood that this will occur when the boat is water-borne. Under this mode of operation, the operating-arm 27 is not manipulated and the tripping-dog has no function. The arm 34 of the support 33, however, will perform its functions when the latch engages the same, as before described. The automatic release of the boat, as just described, can be accomplished either when the boat is loaded, or when it is empty; but, this mode of releasing the boat from the launching-tackle will usually be employed when it is desired to drop the empty boat into the water and allow it to trail by its connection with the painter to the loop or hook 13.

Having thus described my invention, what I claim and desire to secure by Letters Patent is:

1: A releasing-gear for life-boats comprising holding means, locking means, a latch to release the latter, means for supporting the latch, and means for positively holding the latch from movement.

2. A releasing-gear for life-boats comprising holding means, locking means, a latch to release the latter, means for supporting the latch, and a locking-pin for engaging the supporting-means for positively holding the latter in its functional position.

35 3. A detaching-gear for life-boats comprising a holding-bar and means for holding the same in its functional position; means co-operating with the holding-bar for retaining the latter in its functional position.

ing the launching-tackle; and means for positively holding the retaining means in functional position.

4. A detaching-device for life-boats comprising means for retaining the launching-tackle, a latch for holding the retaining means in functional position, a tripping means for the latch comprising a tripping-dog provided with a hook and cam-surface, and a pin carried by the latch for coöperation with the cam-surface and with the hook to prevent the latch from losing coöoperative engagement with the said dog. 40 45

5. In combination with a boat, a duplex pulley or drum; a pair of cables connected at substantially opposite points to the pulley and extending in opposite directions around the same; means for adjusting the parts of the pulley relatively to take up the slack of the cable; detaching-devices secured at opposite ends to the boat; and means connecting the cables with the detaching-devices whereby the latter may be operated by the cables. 55

6. A means for operating releasing-devices carried by boats comprising a supporting-bracket; a two-part pulley journaled in the bracket having means for securing cables thereto, means whereby one part of the pulley may be adjusted circularly relatively to the other, the journal of the pulley having one end squared; and an operating handle having one end fitted upon the squared end of the journal whereby to operate the pulley. 60 65

CHARLES HUNT.
